C. E. FOOTE

THREE-WAY VALVE

Filed April 15, 1925

Fig. 1.

UNITED STATES PATENT OFFICE.

CHARLES E. FOOTE, OF NUNDA, NEW YORK, ASSIGNOR TO THE FOOTE COMPANY, INC.,
OF NUNDA, NEW YORK, A CORPORATION OF NEW YORK.

THREE-WAY VALVE.

Application filed April 15, 1925. Serial No. 23,368.

My invention relates to new and useful improvements in three-way valves for concrete pavers, and has for an object to provide a valve mechanism wherein the water may be directed to a storage tank on the paver and from which storage tank the water may be liberated at desired intervals to the mixing drum.

As is well known to those skilled in the art, most of the concrete pavers are provided with storage tanks from which the water is supplied to the mixing drum. This is better practice than running water from a main supply line directly to the mixing drum.

The reason for this is that the pressure of the main supply line may vary between very great limits and it is therefore preferable to provide a storage tank which can be refilled or be refilling between the intervals when the water is being supplied to the mixing drum.

One of the present objects of the invention is to also provide a three-way valve which is balanced so that the operation of the valve will not require hard manual labor.

Still another object of the invention is to provide a three-way valve wherein the majority of the parts are of metal, only two rubber gaskets or rings being used in the entire valve mechanism.

The valve in its broadest aspect is somewhat similar to the valve shown in the patent to E. H. Lichtenberg, No. 1,525,100, but in that valve a balancing piston is shown which is pivotally connected to the valve stem and this balancing member is provided with leather or other flexible material which is bound to wear in service and will often need replenishing. Also, the casing has certain chambers therein that are difficult to cast, and springs and other members are necessary. The construction hereinafter to be described is more simple in construction and more lasting in service and contemplates but one main valve stem on which is cast or formed a piston adapted to travel in a cylinder and which piston provides the balancing action during the operation of the valve.

Still another object of the invention is to provide a valve mechanism comprising but relatively few parts, capable of simplicity

of operation, readily and quickly assembled, and relatively cheap to manufacture.

With these and other objects in view, the construction consists in certain new and novel arrangements and combination of parts as will be hereinafter more fully described and pointed out in the claims.

Referring now to the drawings, showing a preferred embodiment of my invention,

Fig. 1 is a fragmentary side elevation of a portion of a paver showing a storage tank for the water and my improved valve being shown in section, and the valve in the position for supplying water to the storage tank, and

Fig. 2 is a perspective of the piston having the integral valve stem.

Referring now more specifically to the drawings, there is shown a portion of a frame 1, of a concrete paver on which is mounted a storage tank 2 for the water, a main supply pipe 3 being shown extending to my improved valve 4. Leading from the bottom of this valve is a pipe 5 which is designed to furnish the water to the drum of the paver, not shown. From one of the sides of the valve 4 is shown the pipe 6 which extends within the storage tank 2 to thus supply the tank with water.

Referring now more in detail to my improved valve 4, it will be seen that it consists of an upper casing 7 in which is the cylinder 7' and is provided at its top with a stuffing box 8, while on one side of the casing is formed an extension 9 having the inlet port 10 formed therein to which port leads the main supply pipe 3.

On top of the extension is pivoted the link 11 to which in turn is pivoted the cross bar 12, which in turn is connected to the rod 13 operated by a rod 14 through the bell crank lever 15. A handle, not shown, will be connected to the rod 14 to transmit motion through the several rods to the cross bar 12 to thus raise and lower the same.

Operating within the cylinder 7 is the piston 16 which is provided with the two ears 17 at its upper end, a bolt securing the cross bar 12 to the ears of the piston so that an operation of the rod 14 will raise and lower this piston through the medium of the cross bar 12. The lower end of the cylinder 7' is provided with a circular flange 18

which flange provides a restricted opening for this cylinder, or in other words, provides a valve seat and an outlet port 18' which will be opened and closed by the operation 5 of the piston, as will be shortly described.

The piston extends downwardly in this cylinder opposite the inlet port 10, and may have the short skirt 19 formed thereon for strengthening the same. Integrally and 10 centrally of this piston is the stem 20 which extends through the opening or port 18' into a second chamber 21 formed in the casing 22. This casing has the opening 23 in the bottom thereof which forms an outlet 15 port and there is also provided another port 24 to which is connected the pipe 6 heretofore referred to. A flanged ring 25 is preferably threaded about the pipe 5 and this flanged ring is bolted to the bottom of the 20 casing 22, and likewise the upper casing 7 is bolted to the top of this casing 22.

The lower end of the stem 20 carries a metal washer 26 designed to hold a rubber 25 gasket or ring 27 in contact with a small metal rim 28 and a further rubber ring 29 is held on the bottom surface of this metal rim 28 by a small plate 30 fitted about the stem and in turn held in place by the nut 31 threaded onto the lower end of the stem 20.

30 When the valve is in the position shown, the water will enter the inlet port 10 and flow beneath the piston and through the lower opening 18' in the chamber 7 to the chamber 21 and as the valve stem is in its 35 lowermost position, the rubber ring 29 will close the outlet port 23 (which leads to the drum) and the water will flow through the outlet port 24 to fill the storage tank 2.

Inasmuch as the pressure will be exerted 40 against the head of the piston and against the valve member on the stem, the pressure will be substantially balanced, making it easier to raise the piston and valve stem when desired.

45 To operate the valve, the rod 14 will be pulled outwardly, which in turn will operate the cross bar 12 to thus elevate the piston, and the valve stem being a part of the piston will also be raised, and in this instance, 50 the gasket or ring 27 will seat on the under surface of the flange 18, thereby closing the opening 18' and as this opening is smaller in diameter than the diameter of the piston head, the pressure from the main supply 55 will tend to hold the piston in its uppermost position. The raising of the piston has also opened the outlet 23, thus allowing the water from the storage tank to flow from the pipe 6 and through the chamber 21 to the drum 60 of the mixer by way of the pipe 5.

From the foregoing it will be seen that I have provided a very simple and economical form of balanced valve, wherein the water may be supplied to the storage tank from any main supply, and by the operation

of the valve, the supply to the storage tank will be cut off, and simultaneously permit the water to flow from the storage tank to the mixing drum.

Furthermore, the rubber rings are the only 70 parts subjected to appreciable wear, and these may be quickly renewed with but little loss of time. Again, by providing the valve stem cast integral with the balancing piston, the life of the valve as a whole will be 75 greatly lengthened and require little or no attention.

Furthermore, it will be seen that the casings are very simple in form and are easily 80 cast after which they may be machined and bolted together; that by providing a stuffing box and packing the gland the piston may be well lubricated and will need no attention. Lastly, by forming the stem integral 85 with the piston, there is no lost play in the stem; the action is direct, and the several ports will be tightly closed on the operation 90 of the piston. There are no springs or pivotal connections within the valve to get out of order or out of alignment.

95 Many slight changes might be made without departing from the spirit and scope of the invention.

Having thus described my invention, what I claim as new and desire to secure by Letters Patent is:—

1. In a valve construction, a valve body comprising two superimposed chambers, said chambers provided with openings so that the water may flow from the upper 100 chamber to the lower chamber, the upper chamber provided with a main supply port and the walls of the upper chamber forming a cylinder for the reception of a counterbalancing piston, the lower chamber provided with a discharge opening in its bottom and on one of its sides, a counterbalancing piston within the cylinder formed by the upper chamber walls and having an integral stem extending into the lower of said chambers and provided with closure means thereon to close the lower opening in the upper chamber and the discharge opening in the bottom of the lower chamber, and means for 105 operating the piston to thereby selectively 110 close either of said last mentioned openings.

2. A three way valve mechanism for concrete mixers comprising an upper and lower casing, said casings having opposed valve seats therein, the walls of the upper casing 120 forming a cylinder for the reception of a counterbalancing piston, the upper casing provided with an inlet and outlet opening, the lower chamber provided with an inlet and two outlet openings, a piston operable 125 in said cylinder having a valve stem formed thereon and extending into the lower chamber, a valve closure means on said stem and operating between said opposed seats, the said piston forming pressure counterbalanc- 130

ing means, and means connected externally of said upper chamber and to said piston for operating the said piston and its valve closure means connected thereto.

5. 3. In combination with a water supply line, a water storage tank therefor, a three way valve controlling the passage of the water from the pipe line to the tank and from the tank to a mixer, the said three way valve comprising two casings superimposed and arranged with opposed valve seats and provided with openings so that the water may flow from the upper chamber to the
- 10 lower chamber, said upper casing provided with an inlet port, the lower casing provided with two outlet ports, the walls of the upper chamber forming a cylinder for the reception of a counterbalancing piston, a counterbalancing piston operable in said cylinder and provided with valve closure means, and means for operating said piston to selectively control the closing of either valve seat to thereby direct the water to the tank or to the mixing drum.

In testimony whereof I affix my signature.
CHARLES E. FOOTE.
